(57) **CLAIM**

I claim the ornamental design for a guitar pick with an ergonomic shape, as shown and described.

DESCRIPTION

FIG. 1 is a perspective view of a guitar pick with an ergonomic shape, illustrating a first embodiment, showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a perspective view of a second embodiment thereof;

FIG. 9 is a top plan view thereof;

FIG. 10 is a bottom plan view thereof;

FIG. 11 is a front elevational view thereof;

FIG. 12 is a rear elevational view thereof;

FIG. 13 is a left-side elevational view thereof; and,

FIG. 14 is a right-side elevational view thereof.

The broken lines in FIGS. 3 and 10 represent the portions of the design, which forms no part of the claim.
